UNITED STATES PATENT OFFICE.

HARRY H. STEPHENS, OF PHILADELPHIA, PENNSYLVANIA.

CENTRIFUGAL MACHINE.

1,175,317.

Specification of Letters Patent. Patented Mar. 14, 1916.

Application filed July 25, 1914. Serial No. 853,224.

To all whom it may concern:

Be it known that I, HARRY H. STEPHENS, a citizen of the United States, residing in the city of Philadelphia, county of Philadelphia, and State of Pennsylvania, have invented a new and useful Centrifugal Machine, of which the following is a specification.

My invention relates to centrifugal machines for the extraction of liquids from solids, fabrics or fibrous material, and for similar purposes.

My invention resides in apparatus of the character above referred to and particularly suitable for the extraction of oil from and the cleansing of oily waste or the like, such apparatus involving structure whereby the drum or basket may be rotated by any suitable motor, and when such motor is a steam turbine the exhaust steam is employed for applying heat to the basket contents; and my invention resides further in structure whereby cleansing material may be introduced into the basket, and in other features.

For an illustration of one of the forms my invention may take, reference is to be had in the accompanying drawings, in which:

Figure 1 is a vertical sectional view, some parts in elevation, through apparatus embodying my invention. Fig. 2 is a horizontal sectional view, some parts in plan, taken on the line X—X of Fig. 1. Fig. 3 is a horizontal sectional view taken on the line Y—Y of Fig. 1.

A suitable standard or base 1, which may be of cast iron, is surmounted by a curb or chamber 2, which may be of cast iron, which has beneath its bottom 3 a chamber formed between the bottom 3 and the second or lower bottom 4, the inner wall of the chamber being at 4'. And the bottom 3 at its center is formed into the upwardly extending tube or pipe 5.

Upon the curb or member 2 may be secured by bolts 6 of the ring shaped member 7 to which may be held by clamps 8 the removable cover 9 having the dome 10 and the handles 11.

A spider or bracket 12, carried by the pedestal 1, has the central socket 13 in which may oscillate or gyrate a ball member 14 upon the lower casing member 15 which with the casing member 16 forms the casing of a steam turbine comprising the rotor 17 carrying the peripheral buckets 18. Any suitable nozzle, not shown, extends through the wall of the casing 16 and delivers steam

against the buckets 18 in the well-known manner. The exhaust steam passes out through the opening 19, in the turbine casing and passes thence through the flexible hose 20 and connection 20' into the chamber between the members 3 and 4 and thence through the exhaust opening 21 to the atmosphere or condenser. Secured upon the casing member 16 is the bearing bracket 22 60 steadied against lateral movement by a plurality of rods 23, each carrying at its inner end a ball 24 engaging in a socket on the member 22, each rod 23 carrying at its outer end a buffer member 25 between which and the bracket 26 on base 1 is confined a spring 27. The member 22 carries the ball bearings 28 and 29 for the sleeve 30 secured upon the shaft 31, the shaft 31 extending downwardly through the stuffing box 32 and through the casing member 16, the rotor 17 being secured upon the shaft 31 within the turbine casing. The sleeve 30 is confined between the shoulder 33 on the shaft 31 and a collar 34 secured to the shaft 31 by pin 35. On the upper end 75 of the hollow cylindrical member 22 may be provided a cap 36. Secured to the shaft 31 between its shoulder 37 and the nut 38 threaded on the shaft 31 is the hub 39 of the hollow cylindrical member 40 which embraces the stationary member 5, through which the rotary shaft 31 extends. At its lower end the member 40 has the horizontal disk-like extension 41 secured by rivets 42 to the bottom 43 of the drum or basket 44. 80 As seen in Fig. 1 the member 41 is spaced from said bottom 43 and with this space communicates a pipe 45 supported by a bracket 46 on member 40. A similar pipe 45' 85 may be supported symmetrically with respect to the shaft 45 and serve as a weight to balance the weight of the pipe 45. The pipe 45 extends upwardly through a removable cover 47, having handles 48, which closes the aperture in the inturned flange 49 on the basket 44. A quickly attachable and detachable fluid connection 50 is adapted to connect the pipe 45 with the pipe 51 which swings in a horizontal plane about the pipe connection 52 which extends through the wall of member 2 and communicates with the steam inlet pipe 53 and the water inlet pipe 54. The member 41 has a plurality of perforations 55 forming communication from the space between members 41 and 43 90 and the inferior of the basket 44.

The operation is as follows: The oily

waste or other material to be operated upon is placed in the basket 44 and the covers replaced. The turbine is then started and the same rotates the shaft 31 and the attached basket 44 at high speed, and due to centrifugal action the oil or other material passes out through the perforations in the basket 44 to the interior of the member 2 and passes out through the oil outlet or drain 56, Fig. 10 2, the water outlet 57 being suitably closed, as by a valve in the pipe connecting with the opening 57. The exhaust steam from the motor passes through passage 19, flexible hose 20 and the connection 20' into the space 15 beneath the bottom 3, heating the same, heat being transferred through the bottom 3 to the interior of the curb 2 thus heating the basket and its contents and rendering the separation of the liquid or oil the easier, 20 without adding water or condensed steam to either the waste or oil, the exhaust steam passing out through the passage 21 as before stated. And steam may be admitted into the curb 2 through pipes 53 and 51 when the latter is disconnected from pipe 45. 25

After a suitable time the steam supply to the turbine is discontinued, and by pressing upon the lever 58 outside of the curb 2 and pivoted at 59, the brake shoe 60 within curb 30 2 is caused to press against the under side of the basket 44 to bring the same quickly to rest. Then the cover 9 is removed and the pipe 51, previously detached from the pipe 45, is swung over into alignment with the 35 pipe 45 and connected therewith by the connector 50. The waste or other content which has been impacted on the inner wall of the basket is spread into the body of the basket and, if desired, soap or washing powder may be added. Then steam and water 40 are admitted through pipes 53 and 54, pass into the space between member 41 and the bottom 43 and thence upwardly through the passages 55 into the basket, thoroughly agitating and washing the waste or other contents of the basket. In the meantime the pipe connecting with the oil outlet 56 has been closed, as by a valve. The water and the condensed steam rise within the basket 45 44 and the curb 2 to the height of the overflow 61 and flow out through a pipe connected thereto. The member 5 serves as a dam and extends above the level of the overflow 61 to prevent water passing down 50 around shaft 31 and escaping below. The pipe 51 is again disconnected from pipe 45 and the covers replaced and the turbine again started to rotate the basket 44 at high speed whereupon the washing water is centrifugally extracted and flows out through the opening 57, the valve in the pipe connecting with 57 having been opened. And the continued application of heat from the exhaust steam more or less completely dries 55 the waste or other material. By this treat-

ment the oil or other material is first extracted and then the contents of the basket may be washed and cleaned as described.

During the rotation of the shaft 31, basket 44 and the turbine oscillate as a unit on the member 14, and the oscillations are damped through the rods 23.

What I claim is:

1. The combination with a centrifugal basket, of a pipe rotatable therewith, a double bottom for said basket forming a chamber with which said pipe connects, and a plurality of perforations affording communication between said chamber and the interior of said basket. 75

2. The combination with a centrifugal basket, of a pipe rotatable therewith, a double bottom for said basket forming a chamber with which said pipe connects, a plurality of perforations affording communication 85 between said chamber and the interior of said basket, and means for detachably connecting said pipe with a fluid supply.

3. The combination with a centrifugal basket, of a pipe rotatable therewith, a double bottom for said basket forming a chamber with which said pipe connects, a plurality of perforations affording communication between said chamber and the interior 95 of said basket, and means for detachably connecting said pipe with a supply of steam and water. 90

4. The combination with a centrifugal basket, of a pipe rotatable therewith, a double bottom for said basket forming a chamber with which said pipe connects, a plurality of perforations affording communication 100 between said chamber and the interior of said basket, a casing surrounding said basket, a fluid connection extending through said casing, and means for detachably securing said pipe with said fluid connection. 105

5. The combination with a centrifugal basket, of a pipe rotatable therewith, a double bottom for said basket forming a chamber with which said pipe connects, a plurality of perforations affording communication 110 between said chamber and the interior of said basket, a casing surrounding said basket, a pipe extending through the wall of said casing, and a swinging pipe connecting therewith and adapted to be detachably connected with said first named pipe. 115

6. The combination with an oscillatory rotating shaft, of a hollow member secured 120 on the upper end of said shaft and extending downwardly along said shaft and spaced therefrom, a centrifugal basket secured at its bottom to said hollow member, a curb inclosing said basket, and a stationary sleeve 125 at the center of said curb extending upwardly beyond said basket into the space between said hollow member and said shaft, said sleeve being open and free of said shaft at its upper end, said hollow member and 130

5 said shaft oscillating with respect to said sleeve.

7. The combination with an oscillatory rotating shaft, of a hollow member secured on the upper end of said shaft and extending along said shaft, a centrifugal basket secured to said hollow member, and a dam embracing said shaft and disposed between said shaft and said hollow member. 70

10 8. The combination with an oscillatory rotating shaft, of a hollow member secured on the upper end of said shaft and extending along said shaft, a centrifugal basket secured to said hollow member, and a casing 15 inclosing said basket and a hollow extension on the bottom of said casing extending upwardly along said shaft between said shaft and said hollow member.

9. The combination with a turbine casing 20 and its rotor, of an oscillatory support for said casing, a shaft secured to said rotor and oscillating with said casing, a centrifugal basket driven by said shaft, a casing inclosing said basket, a hollow bottom for said 25 casing, and a connection for steam exhausting from said turbine into said hollow bottom.

10. The combination with a turbine casing and its rotor, of an oscillation bearing at 30 the lower side of said casing, a shaft oscillating with said casing and secured to said rotor, a centrifugal basket secured upon said shaft above said turbine, a casing for said basket, said casing having a hollow bottom, 35 and a connection from said turbine to said hollow bottom for delivering exhaust steam thereto.

11. The combination with a rotary shaft, 40 of a hollow member secured to the upper end of said shaft and extending downwardly and embracing said shaft, a centrifugal basket secured to said hollow member, a casing for said basket, an overflow opening in said casing, and an extension on the bottom of said casing extending upwardly and around said shaft between said shaft and said hollow member to a point above said overflow opening.

12. The combination with a rotating 50 shaft, of a hollow member secured on the upper end of said shaft and extending downwardly along said shaft, a flange on said hollow member at its lower end, a centrifugal basket, the bottom of said basket 55 secured to said flange and spaced therefrom, said bottom and flange forming walls of a chamber, one of said walls having perforations providing communication between said chamber and the interior of said basket, and 60 means for conducting fluid into said chamber.

13. The combination with an oscillatory rotating shaft, of a hollow member secured on the upper end of said shaft and extending 65 downwardly along said shaft, a flange

on said hollow member at its lower end, a centrifugal basket, the bottom of said basket secured to said flange and spaced therefrom to form a chamber, said flange having perforations communicating with said chamber and with the interior of said basket, and a pipe rotatable with said basket and communicating with said chamber. 70

14. The combination with an oscillatory rotating shaft, of a hollow member secured 75 on the upper end of said shaft and extending downwardly along said shaft, a flange on said hollow member at its lower end, a centrifugal basket, the bottom of said basket secured to said flange and spaced therefrom 80 to form a chamber, said flange having perforations communicating with said chamber and with the interior of said basket, a pipe rotatable with said basket and communicating with said chamber, and means for 85 detachably connecting said pipe with a fluid supply.

15. The combination with an oscillatory rotating shaft, of a hollow member secured on the upper end of said shaft and extending 90 downwardly along said shaft, a flange on said hollow member at its lower end, a centrifugal basket, the bottom of said basket secured to said flange and spaced therefrom to form a chamber, said flange having 95 perforations communicating with said chamber and with the interior of said basket, a casing surrounding said basket and having an overflow outlet, and a dam embracing said shaft and disposed between said shaft and said hollow member and extending above 100 said outlet.

16. The combination with an oscillatory rotating shaft, of a hollow member secured 105 on the upper end of said shaft and extending downwardly along said shaft, a flange on said hollow member at its lower end, a centrifugal basket, the bottom of said basket secured to said flange and spaced therefrom to form a chamber, said flange having 110 perforations communicating with said chamber and with the interior of said basket, a pipe rotatable with said basket and communicating with said chamber, a casing surrounding said basket and having an overflow outlet, 115 and a dam embracing said shaft and disposed between said shaft and said hollow member and extending above said outlet.

17. The combination with an oscillatory rotating shaft, of a hollow member secured 120 on the upper end of said shaft and extending downwardly along said shaft, a flange on said hollow member at its lower end, a centrifugal basket, the bottom of said basket secured to said flange and spaced therefrom 125 to form a chamber, said flange having perforations communicating with said chamber and with the interior of said basket, a pipe rotatable with said basket and communicating with said chamber, means for detach- 130

ably connecting said pipe with a fluid supply, a casing surrounding said basket and having an overflow outlet, and a dam embracing said shaft and disposed between said shaft and said hollow member and extending above said outlet.

18. The combination with a centrifugal basket, of a stationary curb inclosing the same, a shaft, a hollow member secured on 10 the upper end of said shaft and extending downwardly along said shaft and spaced therefrom, said basket secured to said hol-

low member, and a hollow extension on the bottom of said curb extending into the space between said hollow member and said shaft, 15 said shaft oscillating and rotating within said hollow extension.

In testimony whereof I have hereunto affixed my signature in the presence of the two subscribing witnesses.

HARRY H. STEPHENS.
